HYDRO-MASSAGE UNIT

Charles S. Benson, 11600 Montana Ave.,
West Los Angeles, Calif.

Filed Oct. 7, 1963, Ser. No. 76,888

Term of patent 14 years

(Cl. D83—1)

FIG. 1.

FIG. 2.

FIGURE 1 is a perspective view of a hydro-massage unit showing my new design; and,

The opposite side from that shown in FIGURE 2 is a mirror image thereof.

I claim:

The ornamental design for a hydro-massage unit, substantially as shown and described.
